SYSTEM OF OPERATION OF TRANSLATING MECHANISMS

Walter S. Lemmon and Austin Robert Noll, New York, N. Y., assignors to International Business Machines Corp., New York, N. Y., a corporation of New York

Application December 7, 1934, Serial No. 756,412

3 Claims. (Cl. 197—90)

This invention relates to a system of operation of translating mechanisms, and more particularly to the operation of a plurality of translating mechanisms controlled by indicia record means, and provides, broadly for indicia record control means to operate the plurality of translating mechanisms simultaneously or to operate any one or all mechanisms independently and in succession, or selectively.

5 A translating system of the type above referred to is disclosed in the application for U. S. Letters Patent Serial No. 753,254 of November 16, 1934. In said prior application one preferred form of translating system and mechanism is shown whereby several typewriting mechanisms are controlled and operated by several electrical sensing devices cooperating with several perforated master control sheets so that the mechanisms are operated individually and in succession, and upon the completion of this 10 operation are then operated simultaneously in accordance with the perforated representations. One control sheet controls the individual operation of the mechanisms and provides for automatically rendering it inoperative when the second control sheet is rendered operative to control the simultaneous operation of the mechanisms.

15 However, with the system disclosed in the said prior application it is seen that the system is limited in its flexibility, that is, the provision of extra mechanisms to be operated by the master control means requires a change in its cyclic operation, secondly, selective operation individually or simultaneously requires various 20 circuit modifications for each separate selection desired, thirdly the provision is made for double master control operation only.

25 Similarly, as in the prior application referred to, in the disclosure of the present invention, for purposes of illustrating the principle of operation one type of indicia record control means will be embodied, and which is in part in the form of a tape sheet or ribbon on which characters or other indicia to be reproduced are represented by perforations to selectively operate the particular associated translating mechanisms, one form of which as shown may be a conventional typewriter.

30 The present system is particularly applicable to automatic letter writer systems whereby individual letters having similar body forms may be typewritten and in addition have the addresses of the particular letters typewritten 35 automatically instead of typing them manually,

and also have different insertions made in the individual letter bodies during the typing operation of the body forms.

To accomplish this procedure automatically, one or two perforated rolls or sheets are provided, as desired. The roll or rolls control the independent operation of the individual typewriters to complete the particular addresses in a manner so that the operation of any individual typewriter for the addressing renders all the others inoperative during that period, in addition thereto, the typewriters may be operated selectively and not necessarily in succession. Upon the completion of typing the individual addresses the system is automatically controlled 15 to operate all the connected typewriters simultaneously to type the common part of the letter on all the machines. During this operation it may be desired to insert in the letter bodies individual representative matter such as the 20 individual names of the parties and then after such individual insertion continue with the common part of the letter body, provision is made so that an individual typewriter may be selected during the simultaneous operation of all the 25 typewriters, and operated, and at the same time render the remaining machines inoperative. One or all of the machines may then be operated individually before continuing the simultaneous operation again.

30 It is therefore one object of the present invention to provide for selective operation of the associated mechanisms independently and simultaneously.

Another object of the present invention is to 35 provide for selective operation of the mechanisms independently and automatic selective simultaneous operation of all the mechanisms.

Still another object of the invention is to provide for selective operation of the mechanisms 40 independently and simultaneously upon completion of the independent mechanism operation.

Still another object is to provide for independent operation of the mechanisms and simultaneous operation of any selected number from the 45 plurality of associated mechanisms.

Still another object is to provide for selective independent operation of the mechanisms when all of them are being operated simultaneously.

Still another object is to provide automatically 50 for successive operation of the mechanisms and selective simultaneous operation.

Still another object is to provide for operation of all the mechanisms simultaneously and to render inoperative all the other mechanisms upon 55

the selection of one to be operated independently.

Still another object is to provide a plurality of indicia record control means for controlling the mechanisms and rendering one inoperative 5 when another is operative.

Still another object is to provide for a single indicia record control means to control the outlined operation of the mechanisms.

Further and other objects of the present invention will be hereinafter set forth in the accompanying specification and claims and shown in the drawings which by way of illustration is what we now consider to be the best mode in which we have contemplated applying that principle. Other embodiments of the invention employing the same or equivalent principle may be used and structural changes made as desired by those skilled in the art without departing from the present invention and within the spirit of 15 the appended claims.

In the drawings:

Fig. 1 shows a schematic diagram embodying a preferred form of the invention with controlling means employed therein consisting of two 25 perforated sheets.

Fig. 2 shows a partial modification of the circuit disclosed in Fig. 1 with controlling means employed therein consisting of a single perforated sheet.

30 Sensing mechanism

Referring to Figure 1, 8 indicates generally the preferred form of sensing device for controlling the typewriters T-1 to T-4 which may be of 35 any conventional type whereby the character key bars and the corresponding type bars (not shown) are controlled by the associated solenoids CM-1 to CM-4 to effect printing the characters. The following brief description of 40 the sensing device will be sufficient, since a more complete disclosure is made in the copending application Serial No. 743,208, filed September 8, 1934, and which as shown is provided with a horizontal transverse conducting roller 10 which 45 supports and feeds the elongated perforated sheet 23 designated AR as the address roll and wide enough to contain a longitudinal series of perforations for the control of each corresponding sensing brush PA and CA.

It is adapted so that the position of a single 50 perforation on the sheet indicates the particular character representation. Therefore when the sheet is fed continuously to the sensing device by suitable means, such as motor 12, and when the particular brush CA senses its corresponding character perforation, a solenoid CM 55 is energized to depress a corresponding key bar and type bar to record the character corresponding to the character perforation sensed.

A complete description of this operation will 60 be set forth hereinafter. In addition to the character sensing brushes CA of which there are as many as character key bars to be operated by the solenoids CM, control brushes PA are provided for purposes to be explained hereinafter.

65 Sensing device 9 is similar in every respect to the device just described with the exception that there are fewer control brushes PL the purpose of which will be evident as the description progresses.

70 Double step relay

One of the character sensing brushes CA-1 or CL-1 for controlling the key shift solenoid CM-1C to CM-4C of the typewriters is provided 75 to energize magnet 25 of the double step relay

when sensing its corresponding perforation in the roll 23 or 24. In order to type in both upper and lower cases, it is obvious that the key shift key bar must be maintained in its respective position for the particular typing desired. Therefore provision to depress the shift key bar must be made so that the depression is maintained for the period selected for that particular type form. This is accomplished by using a double step relay similar to the type described in the application Serial No. 746,489 filed October 2, 1934, the following brief description of which will be sufficient.

10 Energization of magnet 25 causes its armature 40 and associated arm 41 to rotate cam wheel 15 26 so that its high surface forces contact blade 27 in engagement with contact 28, keeping the said contacts closed to energize the shift solenoid CM-1C and/or CM-2C-4C (the method of selecting the particular solenoid or solenoids 20 to be described hereinafter) depending on the particular typewriter operated. The said solenoid remains energized so long as the contacts 27 and 28 are closed, obviously printing the records in the same case during this period. 25

Engagement of the sensing brush CA-1 or CL-1 with another corresponding perforation energizes the magnet 25 thereby stepping the cam wheel 26 ahead to permit the contact blade 27 to engage a lower surface of the cam wheel to disengage the contacts 27 and 28 deenergizing the particular shift key bar solenoid. The slotted cam wheel 26 is provided with half the number of slots as there are teeth in ratchet 42, for example, if the ratchet has twenty teeth and cam wheel 26 half that number of high surfaces, it is obvious that a single operation of the magnet 25 will close and maintain the contacts 27 and 28 closed and a second energization of the magnet will permit the contacts to resume the 40 position shown in the figure. 30

Individual typewriter operation

It will be understood that the perforations are formed by any suitable means and are provided on a sheet or roll wide enough to contain a longitudinal series of perforations for the control of each element of the machine to be operated and used in connection with the translating procedure, that is the type bars and their 50 associated solenoids to actuate the corresponding type bars. 45

Referring to Fig. 1—Let it be assumed that the perforated rolls AR and LR are placed on the corresponding feed rollers 10 and 11 so that 55 when the motor 12 is energized the perforated roll AR is introduced between its corresponding sensing brushes PA and CA and the conducting roller 10 and that the perforations are located so that the typewriters T-1 to T-4 are operated independently and in succession. Upon the completion of the independent operation of the typewriters, the motor 12 will be deenergized and motor 13 energized to feed its perforated roll LR to the corresponding brushes PL and CL to control the plurality of typewriters simultaneously. 60

Upon momentary depression of the start key SK, grounded battery 14 is connected to coil of relay AR-1 through conductor 15, start key contacts SK-1, conductor 16 to ground, energizing said relay and locking itself through its contact ARC-2 as follows; grounded battery 14 to coil of relay AR-1, contacts ARC-2 now closed, conductor 17 and normally closed contact LRB-1 of relay LR-1 to ground. 70

Contact ARC-1 of relay AR-1 is also closed by energization of the said relay to conduct current from grounded battery 14 to motor 12 and ground, causing the perforated roll AR to be fed to the sensing brushes PA and CA cooperatively therewith.

Normally closed contact ARB-1 of relay AR-1 is opened upon energization of this relay, the purpose of which will be explained hereinafter.

- 10 Assume now that a perforation is sensed by the control brush PA-1, current is then conducted from grounded battery 14 through common conductor 18, coil of relay TR-1, conductor 19, its associated brush PA-1, conducting 10
15 roller 10 to ground via contact 20 adapted to engage said roller constantly, energizing relay TR-1. A locking circuit for this relay is established through its now closed contact TRB-1 by connecting grounded battery 14 through conductor 18, coil of relay TR-1, its contact TRB-1, common return conductor 21, normally closed contact LRC-9 of relay LR-1, conductor 22, 20
25 normally closed contacts TRD-4, 3, 2 and contact TRC-1 of relay TR-1 now closed to ground. 25
30 Contact TRA-1 of relay TR-1 is also closed so that by virtue of the connection from grounded battery 14 and conductor 18 to its corresponding armature, the character magnets CM-1 of typewriter T-1 can now be energized when the
35 corresponding character sensing brushes CA engage a perforation in the controlling roll AR, since closure of the said contact TRA-1 permits the energization of magnet TM-1 through the connected conductor 34 thereby closing its contacts TMC-1 disposed in the individual character magnet circuits.

It must be understood that the control brushes PA sensing its corresponding perforation are adapted to engage the conducting roller 10 long enough to permit the corresponding TR relays and LR-1 relay to be energized and establish its corresponding locking circuit to maintain continuous energization of the particular relay.

Upon completion of the type record of typewriter T-1, a similar control perforation is sensed by control brush PA-2 to energize and lock relay TR-2 in a manner similar to that explained for relay TR-1.

It is to be noted that energization of relay TR-2 causes relay TR-1 to be deenergized, that is the locking circuit of relay TR-1 thru its contact TRB-1 is broken momentarily by the movement of the armature engaging the normally closed contact TRD-2, from this said contact to contact TRC-2. It will be remembered that the holding circuit was established through conductor 21, contacts LRC-9, conductor 22, the TRD-4, 3, 2 contacts and TRC-1 contact to ground. Energization of TR-2 relay causes the armature associated with contact TRD-2 to be attracted to contact TRC-2, thereby momentarily breaking the locking circuit from relay TR-1 causing its deenergization.

65 It is evident in order that the energization of one TR relay causes the deenergization of any other TR relay energized it is necessary that the TRC contacts of the TR relays are closed before the TRB contacts are closed by their respective armatures. The adjustment of relay contacts in this manner are well known to those skilled in the art and need not be explained further.

Energization of relay TR-2 permits the independent operation of typewriter T-2 similar-

ly as explained hereinbefore for operation of T-1.

Similarly control brushes PA-3 and PA-4 upon sensing corresponding perforations energize their corresponding relays TR-3 and TR-4 5 separately and successively to permit the independent operation of the associated typewriters T-3 and T-4.

It is necessary to note at this time the provision made for operation of the carriage shift 10 key of the typewriters. In order to record both upper and lower case, it is obvious when upper case is desired that that key must remain depressed for that particular period. The following is what is now considered the preferred method, the carriage shift sensing brush CA-1 engaging a perforation in roll AR indicating a desired shift of type case energizes the solenoid 25 to cause the cam wheel 26 to be rotated so that its high surface forces contact blade 27 in engagement with contact 28 which is fully described in aforementioned application, keeping said contacts closed to energize the carriage shift magnet CM-1C, CM-2C, 3C or 4C depending on the selected TR relay and typewriter to be operated, by connecting grounded battery 14 to the corresponding TRA contact, to its corresponding CM magnets.

The carriage shift magnet remains energized so long as contacts 27 and 28 are closed, obviously causing the records to be printed in the same chosen case during this period. Engagement by carriage shift brush CA-1 of another corresponding perforation indicating a desire to return to the former type case, causes the solenoid 25 to be energized thereby stepping the cam wheel 26 ahead to permit the contact blade 27 to engage a lower surface of the cam wheel to disengage the contacts 27 and 28 to deenergize the carriage shift magnet CM-1C, 2C, 3C 40 or 4C.

Simultaneous typewriter operation

Upon completion of the independent operation of typewriters T-1 to T-4 or any desired plurality control brush PA-5 engaging a perforation on roll AR causes current from grounded battery 14 to be conducted through coil of relay LR-1, energizing the relay and establishing a locking circuit as follows, grounded battery 14, 50 coil of relay LR-1, contact LRC-2 now closed, contact ARB-1 now closed and contact SR-1 now closed to ground.

It should be stated here that the energization of LR-1 relay, opens its normally closed contact LRB-1 to open the ground in the locking circuit for relay AR-1, thereby deenergizing relay AR-1 and restoring its contact ARB-1 to its normally closed position as shown in the figure thereby completing the locking circuit 60 traced for relay LR-1. It is obvious from the disclosure set forth and from the figure that the energization relay AR-1 causes the deenergization of LR-1 and vice versa.

Contacts LRC-1 and ARC-1 of relays LR-1 65 and AR-1 respectively, are adjusted so that they are broken at a definite timed period following the breaking of contacts LRC-2 and ARC-2 and the making of contacts LRB-1 and ARB-1 by their respective armatures so as to insure that when the motors 12 and 13 are deenergized by virtue of contacts LRC-1 and ARC-1 opening the control brushes PA-5 and PL-1 no longer engage the conducting rollers 10 and 11. Delaying the breaking of contacts 75

LRC-1 and ARC-1 insures the rotation of the perforated rolls AR and LR, by the motors, a definite period during which the rolls are advanced so that the corresponding control brushes 5 no longer engage the rollers through these said perforations.

Energization of relay LR-1 causes its contacts LRC-3, 4, 5, 6, and 8 to be engaged by their respective armatures. Engagement of contact LRC-8 by the movement of its armature from contact LRC-9 deenergizes the TR relay that was previously energized to permit operation of its typewriter. The breaking of the TR relay locking circuits was previously explained 15 in connection with the operation of the TRD contacts and needs no further discussion.

Closing of contacts LRC-3, 4, 5, and 6 conducts current from grounded battery 14 by their corresponding conductors 30, 31, 32 and 33 and 20 conductors 34, 35, 36 and 37 to all the TM magnets of all the typewriters T-1 to T-4, permitting the operation of all the typewriters simultaneously upon the respective engagement of the corresponding character sensing brushes CL 25 and the conducting roller 11.

At the completion of simultaneous operation of the typewriters, by virtue of control brush PL-1, energization of relay AR-1 can be established to repeat the operation of typewriters 30 independently as disclosed hereinbefore. Energization of relay AR-1, deenergizes relay LR-1 and motor 13 and energizes motor 12 to feed the controlling roll AR for selective operation of the typewriters T-1 to T-4.

It is obvious from the disclosure given that it is not necessary to select the typewriters T-1 to T-4 in the order described, nor is it necessary to have all the typewriters operated independently before operating them simultaneously. 40 Therefore it is possible to have continuous operation of the typewriters independently, selectively and simultaneously in any manner or order desired by having the control brushes PA and PL engage the perforations and rollers accordingly.

If instead of switching from the roll LR back to the roll AR at the completion of the simultaneous operation of the typewriters, it is desired to stop the mechanism, a preferred method 50 is as follows: Control brush PL-2 sensing a perforation and engaging roller 11 energizes relay SR by conducting current from grounded battery 14 through its coil to ground through the said control brush. Energization of relay 55 SR, deenergizes relay LR-1 by opening its locking circuit previously traced through normally closed contact SR-1. As explained hereinbefore the motor 13 is permitted to rotate the perforated roll so that the last engaged perforation 60 is clear of its associated brush.

Relay SR is deenergized by part depression of start key SK to open the normally closed contacts SK-2. It is obvious when depressing the key SK to start the system disclosed relay SR 65 is deenergized thereby and the operating circuits are properly conditioned thereafter to effect automatic operation of the typewriters in accordance with the perforated control rolls AR and LR.

70 Single roll operation

In Figure 2 it is shown how the arrangement in Fig. 1 can be controlled by a single common roll CR, additional control brushes PA6 and 7 are used to transfer from relays AR to LR, and

for stopping the system at its completion of the operation, and for starting the motor. The additional circuits and their connections are shown and the relays and contacts common to both systems have the same designations, in this manner 5 it will not be necessary to repeat in full the description which was set forth hereinbefore.

Let it be assumed that the perforated roll CR is placed on its feed roller 50 so that when its motor 51 is energized, the perforated roll is introduced between its sensing brushes CA and PA and the said roller, and that the perforations are located so that the typewriters T-1 to T-4 are first operated independently and then operated simultaneously in the following manner. 15

Momentary depression of start key 52 (Fig. 2) energizes relay STR-1 by closing its circuit from grounded battery 14 to energize the motor 51 through its contact STRC-2 connected directly to the said battery. This relay establishes a 20 locking circuit from grounded battery 14 through the coil of the relay, contact STRC-1 now closed, normally closed contact FRC-2 to ground energizing and rotating the said motor and connected feed roller until the described locking circuit is broken.

When the control brushes PA-1 to PA-4 sense their corresponding perforations, the corresponding TR relays are energized to control the operation of the typewriters T-1 to T-4, similarly 30 as described hereinbefore in connection with Fig. 1.

Upon completion of the independent typewriter operation control brush PA-5 sensing a perforation energizes relay LR-1 and locks itself by 35 grounded battery conducted thru the coil of the relay, its now closed LRC-2, normally closed contacts ARB-1 and FRC-1 to ground. The contacts LRC-3 to 6 now closed permit all the typewriters to be operated in accordance with 40 the perforations by virtue of the energization of the TM magnets from grounded battery 14, the LRC-3 to 6 contacts, conductors 30, 31, 32 and 33, conductors 34, 35, 36 and 37, coils of magnets TM-1, 2, 3 and 4 to ground. The TM magnet 45 contacts TMC-1, 2, 3 and 4 remain closed to permit simultaneous operation of the typewriters until the locking circuit described for relay LR-1 is broken.

Provision is made to be able to operate the 50 typewriters selectively and independently during the simultaneous operation of the typewriters, so that at the completion of this independent operation, simultaneous operation can again be continued if so desired or the system can be 55 stopped completely depending upon the predetermined perforated roll, as follows.

Engagement of a perforation by control brush PA-6 allows current from grounded battery 14 to energize the coil of relay AR-1, locking itself 60 through its own contact ARC-2, now closed contact LRB-1, and normally closed contact FRC-3 to ground. Energization of relay AR-1 opened the locking circuit for relay LR-1 at contact ARB-1 to deenergize relay LR-1 restoring its contacts to normal position thereby permitting the locking circuit for relay AR-1 to be established. It is evident that the TM magnets become deenergized upon deenergization of relay LR-1 to open all the circuits to the character solenoids CM. 70

Selective and independent operation of the typewriters controlled now by the TR relays can be effected depending upon the selection of the 75

corresponding control brushes PA-1-4 and fully described hereinbefore.

It has been shown how further energization of control brush PA-5 operates relay LR-1 for simultaneous typewriter operation and concomitantly deenergizes relay AR-1.

Energization of the control brush PA-1 operates relay FR-1 to open its normally closed contacts FRC-1, 2, and 3. The said contacts are opened to break the locking circuits previously described namely, the locking circuits for relays LR-1, or AR-1 and STR-1.

A locking circuit for relay FR-1 need not be provided since a momentary break of the said normally closed contacts is all that is necessary to deenergize any of relays, LR-1 or AR-1 and STR-1 previously energized.

Similarly, as mentioned hereinbefore, contact STRC-2 is adapted to be a slow break contact to insure the operation of motor 51 long enough to feed the perforated roll so that its perforations just sensed are beyond the sensing position and the brushes PA or CA are no longer co-operating with the corresponding perforations. Depression again of the start key 52 locks the relay STR-1 and energizes motor 51 to rotate the feed roller initiating another cycle of operation in accordance with the perforated roll CR.

It is evident from the description set forth that additional TR relays may be provided as shown with corresponding control brushes PA to control the simultaneous operation of selected groups of the typewriters as T-1, T-2 and T-3 excluding T-4 so that further selective simultaneous operation of the typewriters may be obtained.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a system of the class described, record control means, sensing means cooperating there-

with, a plurality of typewriters, individual control relays therefor, means to energize said relays, the circuit connections of said relays arranged so that the energization of one control relay de-energizes any one of the other control relays which may have been energized, said relay maintained energized adapted to render the associated typewriter operative, and means associated with said typewriters controlled by the said sensing means to control the typewriter in accordance with the data sensed on said record control means. 10

2. In a system of the class described, record control means, sensing means cooperating therewith, a plurality of typewriters, controlling instrumentalities for said typewriters, individual control relays for said typewriters, means to energize said relays, the circuit connections of said relays arranged so that the energization of one control relay de-energizes any one of the other control relays which may have been energized, means adapted to connect said typewriter controlling instrumentalities to said sensing means, the said control relay maintained energized adapted to operate the last named means of the typewriter associated with said control relay so as to control the said typewriter in accordance with the data sensed on said record control means. 15 20 25

3. In a system of the class described, perforated record control means, control sensing brushes cooperating therewith, a plurality of typewriters, individual control relays for said typewriters, the energization of which are controlled by certain of said control brushes, the circuit connections of said relays arranged so that the energization of one control relay de-energizes any one of the other control relays which may have been energized, the said control relay maintained energized adapted to render operative the associated typewriter so as to be controlled in accordance with the data sensed by certain other of said sensing brushes, and other relay means operated to connect said individual typewriters in multiple to be controlled in unison by the said sensing brushes 30 35 40 45 in accordance with the data sensed.

WALTER S. LEMMON.
AUSTIN ROBERT NOLL.
